Herbert S. Fairbanks

ATTORNEY.

UNITED STATES PATENT OFFICE

WILLIAM A. RINGLER, OF WAYNE, PENNSYLVANIA, ASSIGNOR TO FRANK A. WEEKS
MFG. CO. INC., OF NEW YORK, N. Y., A CORPORATION OF NEW YORK

MEMORANDUM PAD

Application filed July 11, 1931, Serial No. 550,098. Renewed October 1, 1932.

The object of this invention is to devise a novel construction and arrangement of a memorandum pad which can be employed as a calendar or to hold any desired type 5 of loose leaf sheets.

A further object of the invention is to devise a pad of this character which can be made of a minimum number of parts, only three parts being necessary, the support, a 10 hinge, and the pad carrier, the clips which retain the loose sheets in position being preferably formed integral with the pad carrier.

With the above and other objects in view, as will hereinafter clearly appear, my invention comprehends a novel memorandum 15 pad.

It further comprehends a novel memorandum pad which can be made of three parts, a support, a pad carrier, and a hinge.

20 It further comprehends a novel memorandum pad wherein the memorandum sheets are aligned in position by the pad support and the pad carrier, provision being made for turning the sheets under the pad carrier so that in case of a calendar, for example, the height of the sheets of the memorandum pad will remain constant throughout its use.

Other novel features of construction and 25 advantage will hereinafter more clearly appear in the detailed description and the appended claims.

For the purpose of illustrating the invention, I have shown in the accompanying drawing, a typical embodiment of it, which, in practice, will give satisfactory and reliable results. It is, however, to be understood that the various instrumentalities of which my invention consists can be variously arranged and organized, and my invention is not limited to the exact arrangement and organization of these instrumentalities as herein set forth.

45 Figure 1 is a perspective view of a memorandum pad embodying my invention.

Figure 2 is a perspective view of the pad carrier in detached position.

50 Figure 3 is a top plan view of the pad support in detached position.

Similar numerals of reference indicate corresponding parts.

Referring to the drawing:

1 designates the support of a memorandum pad embodying my invention. This 55 can be readily formed from sheet metal and has its rear end deflected downwardly at 2 and terminating in a base flange 3. The rear end and a portion of the top of the support is slotted as indicated at 4. The forward end of the support 1 is deflected as at 5 so that the proper angle or inclination will be given to the pad.

The forward end of the sheet metal of which the pad support is formed, is deflected 65 upon itself as at 6 to form a hinge connection with the hinge member 7. This hinge member 7 is preferably formed of a single piece of wire bent in a rectangular formation and having its inner stretch hinged as at 8 to the 70 forward end of the pad carrier 9. This pad carrier 9 is also formed from sheet metal and at its rear end is provided with an upwardly extending flange 10 which forms a sheet aligning member. Portions of the material 75 of the pad carrier 9 are cut out as shown in Figure 2 to form the clips 11 which are bent upon themselves and spot welded as at 12. These clips at their free ends are provided with the opposed slots 13 thereby adapting 80 them to interlock with the walls of the slots 14 which open through the rear end of the pad carrier 9.

The side walls of the pad support 1 are preferably upwardly deflected as at 15 to 85 form side aligning members for the sheets and one of these is bent into a loop as at 16 to form a retainer for a pencil, the point of the pencil resting on the base flange 3.

17 designates the sheets which are provided with the apertures 18 through which the clips 11 pass. These clips 11 are looped upon themselves as clearly indicated in Figures 1 and 2 so that as the top sheet is used the pad carrier can be raised and such sheet folded 95 under the pad carrier 9.

It will thus be apparent that the memorandum pad will be of uniform height as it is used, its sheets being properly aligned between the aligning members 10 and 15.

The clips 11 closely fit the walls of the slots 4 so that the pad carrier 9 is always accurately aligned with respect to its pad support 1.

In accordance with my present invention 5 the memorandum pad can be economically manufactured as it consists of only three parts, two of which can be formed from sheet metal and the other of which can be formed from stock rod material.

10 It will of course be apparent that if desired instead of having the clips 11 integral with the pad carrier 9, they may be separately formed and connected therewith in any desired manner.

15 It will now be apparent that I have devised a new and useful memorandum pad which embodies the features of advantage enumerated as desirable in the statement of the invention and the above description, and while

20 I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention what I claim as new and desire to secure by Letters 30 Patent, is:—

1. A memorandum pad, consisting of a pad support, a pad carrier and a hinged member connected with said pad support and pad carrier, said carrier having sheet retaining 35 clips which interlock with the rear portion of the pad support.

2. A memorandum pad, consisting of a pad support and a pad carrier hinged together at one end, said pad support being bent 40 downwardly at its rear end and provided with slots, and said pad carrier having clips to lock with it and pass through the pad sheets and to enter said slots to align the pad support and pad carrier.

45 3. A memorandum pad, comprising a pad support, formed of sheet metal with its side portions upwardly deflected to form side aligning members, and having its rear portion downwardly deflected and provided 50 with slots, a pad carrier formed of sheet metal, a hinge in the form of a rectangular rod over which the forward end of the metal of the pad support and pad carrier is deflected, said pad carrier having clips formed 55 from it and provided with slots to receive the free ends of the clips, said clips being bent in the form of loops to provide for the turning under of the memorandum sheets carried by it, said loops entering the slots in said pad 60 support to retain the latter and the pad carrier in aligned position.

65 4. A memorandum pad, comprising a support deflected downwardly at its rear end and provided with slots, the side portions of 70 said support being upwardly deflected to

form side aligning members, a pad carrier in the form of a plate, a hinge member hinged to the forward end of the pad support and the pad carrier, said pad support having clips which are deflected downwardly and upwardly and provided with slots in their terminal portions, said pad carrier having slots to receive and interlock with said terminals, said pad carrier also having its rear end deflected upwardly to form a sheet aligning member, 75 and said clips being adapted to engage the walls of the slots of the pad support to secure the latter and the pad carrier in aligned position.

5. A memorandum pad, comprising a pad support formed of sheet metal with its sides deflected upwardly, its rear end deflected downwardly and with one of said sides deflected to form a pencil retaining member, a pad carrier, a hinge member hinged to the forward ends of said pad support and pad carrier by deflecting them thereover, said pad carrier having clips in the form of loops extending below and above said pad carrier with their free ends adapted to pass through 80 sheets and be detachably connected with the pad carrier, said pad carrier having at its rear end an upwardly deflected aligning member, and said clips being adapted to enter the slots of said pad support to align the latter with the pad carrier.

6. A memorandum pad, comprising a pad support, a pad carrier arranged thereon, a member connecting and separately hinged to the front portions of the support and carrier, 85 and movable with respect thereto, and sheet retaining clips rigid with the rear portion 90 of the pad carrier.

7. A memorandum pad, comprising a pad support, a pad carrier arranged thereon and movable with respect thereto, and sheet retaining clips cut from the pad carrier and interlocked with the rear portion of the pad carrier.

8. A memorandum pad, comprising a pad support, a pad carrier arranged thereon and movable with respect thereto, and sheet retaining clips cut from and rigid with the rear portion of the pad carrier and projecting 100 away from the opposite surfaces thereof.

9. A memorandum pad, comprising a pad support provided with slots in its rear portion, and a pad carrier arranged thereon and having separate hinge connections therewith so that it is movable with respect thereto, the pad support having a downwardly extending rear portion and said pad carrier having clips to pass through the pad sheets and enter the slots to align the pad support and the carrier.

10. A memorandum pad, comprising a pad support provided with a slot in its rear portion, a pad carrier arranged on the support and movable with respect thereto, and a pad clip on the rear portion of the carrier and ex- 110

tending above and below the carrier, such clip registering with, and adapted to enter, the slot at will when the carrier is moved towards the support.

- 5 11. A memorandum pad, comprising a pad support provided with a slot in its rear portion, a pad carrier arranged on the support and movable with respect thereto, and a pad clip rigidly mounted on the rear portion of
10 the carrier and extending above and below the carrier, such clip registering with, and its lower part adapted to enter, the slot at will when the carrier is moved towards the support.
- 15 12. A memorandum pad, comprising a pad support provided with a rearwardly open slot in its rear portion, a pad carrier arranged on the support and movable with respect thereto, and a pad clip on the rear portion
20 of the carrier and extending above, below and behind the carrier, such clip registering with, and adapted to enter, the slot at will, the clip projecting rearwardly of the slot when it is received therein.
